UNITED STATES PATENT OFFICE.

CHARLES A. REMELIUS, OF NEW YORK, N. Y., ASSIGNOR TO THE PAY-AS-YOU-ENTER CAR CORPORATION, OF JERSEY CITY, NEW JERSEY, A CORPORATION OF NEW JERSEY.

DOOR-OPERATING MECHANISM.

1,167,433.

Specification of Letters Patent. Patented Jan. 11, 1916.

Application filed September 15, 1911. Serial No. 649,591.

To all whom it may concern:

Be it known that I, CHARLES A. REMELIUS, a citizen of the United States, residing in New York, county of New York, State of New York, have invented certain Improvements in Door-Operating Mechanism, of which the following is a specification.

The object of my invention is to provide means for operating the side doors of the platform of a passenger car which will be clear of the passageways leading to and from the body of the car and yet will be exposed so that in the event of repairs access may be readily had to the apparatus.

In the accompanying drawings:—Figure 1, is a vertical sectional view of a car; illustrating my invention; Fig. 2, is a plan view showing the doors in the open position; Fig. 3, is a plan view showing the doors in a closed position; Fig. 4, is a vertical sectional view through the operating device, and Fig. 5, is a detached perspective view of the device illustrating a detail of the invention.

25 A is the body of the car.

B is the platform having the usual front vestibule casing B' and C is the roof of the platform. In the present instance the platform is open at one side and this side is closed by a pair of double doors D and E. Both doors may swing outward, as indicated in Fig. 2, of the drawing. The doors are pivoted at d and e respectively, and these pivots are in the form of rods which extend, in the present instance, the full height of the door, and at the upper end of these rods are arms d' and e'.

F is a bearing secured to the plate F' and attached to the roof of the car. Mounted in this bearing is a vertical shaft G carrying the rope sheave g at its lower end. On the upper end of the shaft is a head g', which rests upon the bearing, and in the present instance there is a ball bearing i mounted between this head and the bearing. A rope h passes around this rope sheave and on each end of the rope is a hand hold. The ropes passing around the grooved guide rollers k, mounted in bearings f, in the present instance, independent of the bearing F. Projecting from the under side of the sheave are two pins g², g³, to which rods n, n' are attached—one rod n being attached to one pin g² and to the arm d' on the pivot rod d, while the other rod n' is attached to the

pin g³ and to the arm e' on the pivot rod e so that when the sheave is rotated—first in one direction, the doors will be opened, and when rotated in the opposite direction, the doors will be closed.

The rods n, n' are so formed that the pins can pass the center line drawn through the pivot of the arms and through the shaft, thus locking the doors in the closed position. Projecting from the bearing F is a stop f' and on the sheave g are lugs m. One of these lugs contacts with the stop when the sheave is turned in one direction and the other lug contacts with the stop when moved in the opposite direction. Mounted in the stop in the present instance are cushions of rubber or other yielding material. Mounted on an extension p of the shaft G is a cup or shield P, which is arranged to catch any oil that may drip from the bearings.

The doors are made in two sections and the doors open outward, in the present instance. The sections D' and E' are mounted on the pivots d and e, while the sections D² and E² are pivoted respectively to the outer ends of the sections D' and E' and fold inward. On these sections D² and E² are pins or rollers d² and e², which travel in an overhead guide rail C' at the roof of the car. The lower ends of the doors may also be provided with rollers, which travel in guideways, but this is not absolutely essential.

The operation of the mechanism is as follows:—When the doors are open, the hand holds are in the position illustrated in Fig. 1, and the conductor is located on the platform in close proximity to the hand holds and by simply pulling down on the one which is the highest the sheave is turned and the doors are moved to the closed position and preferably locked automatically. When it is necessary to open the doors, the other end of the rope is pulled down, causing the sheave to turn in the opposite direction, and the doors are thus moved to the open position.

All of the mechanism, with the exception of the two depending ends of the rope, is above the head line of the car platform, and as this device is generally used on a platform having a guard rail or partition separating the ingress passageway from the egress passageway, the depending ends of the ropes are located in close proximity to

this guard so as not to be in the path of the passengers entering or leaving the car.

I claim:—

The combination in means for operating passenger car doors, of an overhead bearing, a vertical shaft in the said bearing having a head resting on the bearing, and a sheave secured to the shaft under the bearing, pins on the sheave to which the rods are attached leading to the doors to be operated, a stop on the bearing, and lugs on the sheave con-

tacting with the stop to limit the movement of the sheave, and means for rotating said sheave to operate the doors.

In testimony whereof, I have signed my 15 name to this specification, in the presence of two subscribing witnesses.

CHARLES A. REMELIUS.
